UNITED STATES PATENT OFFICE.

GEORGE M. WILDIN, OF MELVERN, KANSAS.

TRUSSSED SUSPENSION-BRIDGE.

SPECIFICATION forming part of Letters Patent No. 399,105, dated March 5, 1889.

Application filed November 22, 1888. Serial No. 291,580. (No model.)

To all whom it may concern:

Be it known that I, GEORGE M. WILDIN, a citizen of the United States, residing at Melvern, in the county of Osage and State of Kansas, have invented a new and useful Improvement in Trussed Suspension-Bridges, of which the following is a specification.

My invention relates to an improvement in trussed suspension-bridges; and it consists in the peculiar construction and combination of devices, that will be more fully set forth hereinafter, and particularly pointed out in the claims.

In the accompanying drawings, Figure 1 is an elevation of a bridge embodying my improvements. Fig. 2 is a transverse sectional view of the same. Figs. 3 and 4 are detail perspective views. Fig. 5 is a top plan view of a portion of a bridge. Fig. 6 is a bottom plan view of the same. Fig. 7 is a detail perspective view.

A represents the chords or stringers, which are slightly arched, as shown, and are supported on the piers B, the outer ends of said chords or stringers projecting beyond the piers for a suitable distance and resting on the banks or approaches.

C represents the posts, which are arranged in pairs on opposite sides of the bridge, have their lower ends passed between the stringers or chords and supported by the piers, and have their upper ends covered by caps or saddles D, which have pairs of ears or flanges E on their upper sides, and are connected together by cross-bars F. The pairs of posts C are braced laterally by arched bars G, which have their centers bolted under the centers of the bars F, and have their ends bolted to the inner sides of the posts C.

The cables H are supported by the posts C, bear upon the saddle-plates D and between the ears or flanges E, and have their ends secured at suitable distances beyond the piers in the banks of the stream or chasm by suitable anchoring devices, I. The chords or stringers are supported by tie-rods K, which depend from the cable, and the said tie-rods are inverted-U shaped, have the arched central portions passed over the plates or castings L, supported on the cables and provided on opposite sides with ears M, having open-

ings, through which the arms of the tie-rods extend. The lower ends of the said arms are arranged on opposite sides of the pairs of chords or stringers, and passed through the laterally-extending arms N of plates or castings O, and provided with nuts P. The said plates or castings O are arranged transversely under the chords or stringers, and are provided with longitudinal arms R, arranged at right angles to the arm N, said arms R being under the spaces which separate the pairs of chords or stringers. The plates or castings L are provided on opposite sides at diagonally-opposite corners with ears S.

T represents the deck-beams, which are arranged transversely on the chords or stringers at suitable distance apart, and on the said deck-beams are secured the flooring-boards U, the latter being arranged diagonally, as shown.

V represents a series of truss-rods, which are substantially V-shaped, have their lower portions extending under the plates or castings N and passed through openings in the arms R, and have their upper ends passed through openings in the ears S and provided with nuts W. The said truss-rods cross each other, as shown in Fig. 1, midway between the tie-rods, and thus serve to distribute the weight of the load on any part of the bridge throughout the entire structure, and thereby enable the bridge to be constructed of comparatively light material without injuriously affecting its strength. The said truss-rods render the bridge very stable and prevent it from undulating under the weight of a moving load, and consequently enhance the durability of the bridge by reducing the friction between its parts to the minimum degree.

X represents hub-boards, which are arranged at a suitable height above the bridge-floor, and are secured to the tie-rods by means of clip-bolts Y. The function of the said hub-boards is to prevent the hubs or vehicles from striking the tie and truss rods when passing over the bridge, the said hub-boards also serving the purpose of a hand-rail, and rendering the bridge safe for pedestrians.

Having thus described my invention, I claim—

1. The combination, in a suspension-bridge,

of the cables, the chords or stringers, the plates or castings on the cables and under the stringers, the vertical tie-rods connecting the plates or castings, and the truss-rods, also secured to and connecting the said plates, the said truss-rods being crossed in the spaces between the tie-rods, substantially as described.

2. The plates or castings L, having the concaved grooves on their lower sides to adapt them to fit on the cables and having the ears M and the ears S, in combination with the tie-rods secured to the ears M, and the truss-rods secured to the ears S, substantially as described.

3. The combination, with the stringers or chords arranged in pairs and apart from each other, the plates or castings O, arranged under the stringers and having the transverse arms N and the longitudinal arms R, the tie-rods secured to the arms N, and the truss-rods secured to the arms R, substantially as described.

4. The combination, in a suspension-bridge, of the cables, the chords or stringers, the tie-rods depending from the cables and supporting the chords, the truss-rods also connecting the cable and chords, the deck-beams arranged on the chords or stringers, the floor-boards supported on the deck-beams, and the hub-boards X, secured to the tie-rods, substantially as described.

5. In a bridge, the piers B, the chords or stringers A, slightly arched and supported by the piers, the ends of the chords or stringers projecting beyond the piers for a suitable distance and resting on the banks or approaches, the posts C, arranged in pairs on opposite sides of the bridge, and having their lower ends passed between the stringers or chords and supported by the piers, the saddles or caps D at the upper ends of the posts C, and the cables H, supported by the posts C by bearing on the saddles D, and having their ends secured at a suitable distance beyond the piers of the stream by suitable anchoring devices, as set forth.

6. The posts C, arranged in pairs on op-

posite sides of the bridge, and having the caps or saddles D provided with ears or flanges E, 50 the said caps or saddles being connected by the cross-bar F, combined with the cables H, supported by the posts C, bearing upon the saddle-plates D between the flanges thereof, and having their ends secured at a suitable 55 distance beyond the piers by suitable anchoring devices, I, as set forth.

7. In a suspension-bridge, the cables, the plates or castings L on the cables, the V-shaped truss-rods V, having their upper ends 60 connected to the plates or castings L, the chords or stringers A, and the plates or castings O below the chords or stringers and connected to the truss-rods V, as set forth.

8. In a suspension-bridge, the chords or 65 stringers A, the cables H, the V-shaped truss-rods V, depending from the cables and passing under the chords or stringers, and the tie-rods K, also depending from the cables, having the shape of an inverted U, and passing 70 down and connected to the chords or stringers, and the truss-rods V, crossing each other midway between the tie-rods K, as set forth.

9. In a suspension-bridge, the cables H, the chords or stringers A, and the truss-rods V, 75 having the shape of the letter V, the central portion of the truss-rods passing under the chords or stringers, and the upper ends being secured to the cables, the said truss-rods crossing each other, as set forth.

10. In a suspension-bridge, the cables H, the chords or stringers A, the plates L on the cables, the plates O below the chords or stringers, and the V-shaped truss-rods V, having 85 their central portions passed through the plates O, to hold the same against the chords or stringers, and their upper ends connected to alternate plates L, the said truss-rods crossing each other, as set forth.

In testimony that I claim the foregoing as 90 my own I have hereunto affixed my signature in presence of two witnesses.

GEORGE M. WILDIN.
